WATER-TUBE BOILER.

1,162,066.

Specification of Letters Patent. Patented Nov. 30, 1915.

Application filed March 10, 1914. Serial No. 823,651.

To all whom it may concern:

Be it known that I, DAVID S. JACOBUS, a citizen of the United States, residing at Jersey City, in the county of Hudson and State 5 of New Jersey, have invented certain new and useful Improvements in Water-Tube Boilers, of which the following is a specification.

My invention relates to water tube boilers 10 and has for its object an increase in the efficiency and capacity in installations of large units. This is effected through a furnace arrangement in which exceptionally high efficiencies are obtained combined with 15 a boiler for economically removing the heat generated in burning the fuel. In certain somewhat similar boilers which have been constructed, where there are three upper steam and water drums and two lower mud drums, there is a limitation to the amount 20 of heating surface which may be installed especially in designs contemplating the use of straight boiler tubes. The present invention overcomes this difficulty and allows for 25 the introduction of any amount of surface that could be desired to meet practical demands. The construction further admits of the introduction of dust pockets for collecting the dust at points where it will not interfere with the passage of the gases through 30 the boiler, which, in itself, is a material advantage.

The invention comprises certain features of construction which will be understood 35 by reference to the accompanying drawing which is a vertical longitudinal section of a boiler showing one embodiment of the invention.

In the design shown there are two inner 40 banks of water tubes 1 and 2 inclined toward each other and expanded at their upper ends into a central steam and water drum 3, and at their lower ends into mud drums 4 and 5, said latter drums extending parallel with 45 drum 3 and from one side wall of the setting to the other side wall, one on each side of the furnace. Inclined to the vertical at substantially the same degree as the inner banks of tubes are two outer banks 6 and 7, the 50 tubes of which are expanded at their upper end into the headers 8 and 9, and their lower ends expanded into headers 10 and 11. The headers 8 and 9 are connected by nipples 12 and 13 with outer steam and water 55 drums 14 and 15, respectively, and the lower

headers 10 and 11 are connected by nipples 16 and 17 with the mud drums 4 and 5, respectively. Spaces between the nipples 16 and 17 permit the dust to fall through into pockets as later described. The steam and 60 water drums 14 and 15 are placed one on each side of the central steam and water drum and parallel therewith, and the central drum is inter-connected with the outer drums by steam circulators 18 and 19, and 65 by water circulators 20 and 21.

Alternate tubes in the front rows of the outer banks of tubes are omitted so as to permit of the expansion into headers 10 and 11 of rows of tubes 22 and 23 expanded at 70 their upper ends into the central steam and water drum alternately with the water circulators 20 and 21. I also introduce rows of tubes 24 and 25, the former expanded into drum 14 and headers 10, and the latter into 75 drum 15 and headers 11.

Baffles 26 and 27 are placed at the rear of the inner banks of tubes and extend upward from the mud drums so as to direct the hot 80 gases from the furnace to the upper part of the two banks except where it is desired to secure a higher furnace temperature than would be secured by exposing all of the tubes of the inner banks to the fire, in which case the baffles 18 and 19 are placed between 85 two rows of the tubes so as to expose only a portion of the tubes of each of the inner banks to the fire. The gases then flow downward and are guided to the lower part of the outer banks of tubes by baffles 28 and 29 supported 90 on the rows of tubes 22 and 23, respectively. After entering the lower part of the outer banks of tubes the gases are made to cross and recross the same by cross baffles 30 and 31, and to take a general upward direction 95 by baffles 32 and 33 supported upon the tubes 24 and 25, respectively. The gases finally pass to the stack connections through the damper openings 34 and 35. In this design the water and steam circulates upward 100 through the tubes of the inner banks and the water from drum 3 flows into drums 14 and 15 through the circulators 20 and 21, thence downward through the tubes of the outer banks and the tubes 24 and 25, and 105 through the headers 10 and 11 and connecting nipples 16 and 17 into the mud drums 4 and 5, from whence it again flows upward through the tubes of the inner banks. The steam generated by the boiler passes from 110

the drums 14 and 15 through the pipes 36 and 37 to two superheaters 38 and 39 placed in the spaces at the rear of the inner banks of tubes, and between said banks and the 5 rows of tubes 22 and 23, the steam being thus divided between the two superheaters and finally discharged therefrom into the mains 40 and 41. The superheaters 38 and 39 may be of any approved design, that 10 shown consisting of U-shaped tubes extending substantially parallel with the tubes of the inner banks with their ends expanded into cross boxes. The superheaters may be omitted if saturated steam only is required. 15 Dust pockets 42 and 43 are provided below the mud drums 4 and 5 into which dust will collect after passing through the spaces between the nipples 16 and 17, and from which pockets it may be withdrawn by any 20 suitable means.

The tubes in the outer banks 6 and 7 may be readily removed, as indicated by the broken lines, by passing them downward through hand hole openings in the headers 25 10 and 11 and new tubes may be inserted by passing them upward through the headers. In the ordinary use of straight tubes connected at both ends to drums it is necessary to allow for removal and replacement of any 30 one of the tubes without removing the others, and to do this sufficient space is left between the tubes, and the spacing and the form of the projections on the drums are so arranged that after cutting out an old 35 tube a new one can be inserted in its place. In inserting the new tube one end of it is passed through the opening in one of the drums and it is then moved over the opening in the other drum and made to enter 40 the latter, after which it is expanded into place. To accomplish this requires a much wider spacing of the tubes than is required in boilers of the present design where the tubes are replaced in the outer banks by 45 passing them upward through hand hole openings in the headers.

The hand hole fittings provided for the removal and replacement of tubes in the headers 10 and 11 need be removed only 50 for replacing tubes, as it is not necessary to remove such fittings in cleaning the tubes by means of standard turbine tube cleaners, which are inserted from the top of the tubes. This removes an objection often 55 raised to the use of a number of such hand hole fittings.

The banks of tubes are suspended over a common furnace 44 extending from the front to the rear of the boiler, the inner banks being so disposed as to converge toward each other upwardly, their upper ends meeting approximately in the transverse central vertical plane of the setting. There is thus provided a large A-shaped combustion chamber substantially closed at the apex

and open to the gases at the upper part of the inclined sides; that is, at the uptake ends of the generating tubes of the inner banks. The gases divide and pass over the heating surfaces, as indicated by the arrows 70 and as previously described.

The furnace may be of any approved type with means for charging it preferably at the front and rear, so as to provide a substantially continuous fuel bed beneath the 75 boiler.

With such arrangement the character of the combustion may be maintained substantially constant from one side of the boiler to the other, and the loss often experienced 80 through a stream or lane of excess air or unconsumed combustible gases passing through the boiler and escaping to the stacks will be avoided. It is well known among engineers that in ordinary boiler furnaces there is a 85 great variation in analyses taken from different points in the path of the flow of gases leaving the furnace, whereas with the present furnace, arrangement this action is reduced to a minimum, as any irregularity 90 from the front to the rear of the grates disappears before the gases pass from the upper part of the combustion chamber, and, as the composition of the gases for uniform 95 firing conditions will be substantially uniform from one side of the boiler to the other, it follows that the composition of the entire volume of the gases leaving the furnace will be substantially uniform.

The angle of inclination of the tubes of 100 the heating surface is approximately 20° to the vertical, but I do not restrict myself to such degree of inclination, the essential feature being the disposition of the banks of tubes over a common furnace and combustion chamber to provide an A-shaped combustion chamber of relatively large volume, and the other features herein described, which contribute to an increased efficiency 105 and economy in operation.

What I claim and desire to secure by Letters Patent of the United States is:—

1. In a water tube boiler, two inner banks of generating tubes inclined toward each other so as to form two sides of an A-shaped combustion chamber, a steam and water drum and two mud drums into which the tubes of said banks are expanded, two outer banks of tubes one on each side of the inner banks, upper and lower headers into which the tubes of the outer banks are expanded, outer steam and water drums, steam and water circulators connecting the intermediate drum with the outer drums, connections between said upper headers and the outer 120 steam and water drums, and connections between the lower headers and the mud drums.

2. In a water tube boiler, two inner banks of generating tubes inclined toward each other so as to form two sides of an A-shaped 125 130

- combustion chamber, a steam and water drum and two mud drums into which the tubes of said banks are expanded, two outer banks of tubes one on each side of the inner banks, upper and lower headers into which the tubes of the outer banks are expanded, outer steam and water drums, steam and water circulators connecting the intermediate drum with the outer drums, connections between said upper headers and the outer steam and water drums, connections between the lower headers and the mud drums, and baffles to direct the hot gases to the upper part of the inner banks of tubes, thence downward to the lower part of the outer banks, and thence upward over the tubes of the outer banks.
3. In a water tube boiler, two inner banks of generating tubes inclined toward each other so as to form two sides of an A-shaped combustion chamber, a steam and water drum and two mud drums into which the tubes of said banks are expanded, two outer banks of tubes one on each side of the inner banks, upper and lower headers into which the tubes of the outer banks are expanded, outer steam and water drums, steam and water circulators connecting the intermediate drum with the outer drums, connections between said upper headers and the outer steam and water drums, connections between the lower headers and the mud drums, rows of tubes connecting the intermediate steam and water drum with said headers, baffles supported on said tubes, and baffles to direct the gases to the upper part of the inner banks of tubes.
4. In a water tube boiler, two inner banks of generating tubes inclined toward each other so as to form two sides of an A-shaped combustion chamber, a steam and water drum and two mud drums into which the tubes of said banks are expanded, two outer banks of tubes one on each side of the inner banks, upper and lower headers into which the tubes of the outer banks are expanded, outer steam and water drums, steam and water circulators connecting the intermediate drum with the outer drums, connections between said upper headers and the outer steam and water drums, connections between the lower headers and the mud drums, superheaters in the spaces between the inner and outer banks of tubes, and connections between the outer steam and water drums and said superheaters.
5. In a water tube boiler, two inner banks of generating tubes inclined toward each other so as to form two sides of an A-shaped
- combustion chamber, a steam and water drum and two mud drums into which the tubes of said banks are expanded, two outer banks of tubes one on each side of the inner banks, upper and lower headers into which the tubes of the outer banks are expanded, outer steam and water drums, steam and water circulators connecting the intermediate drum with the outer drums, connections between said upper headers and the outer steam and water drums, connections between the lower headers and the mud drums, and rows of tubes connecting the intermediate steam and water drum with said headers.
6. In a water tube boiler, two inner banks of generating tubes inclined toward each other so as to form two sides of an A-shaped combustion chamber, a steam and water drum and two mud drums into which the tubes of said banks are expanded, two outer banks of tubes one on each side of the inner banks, upper and lower headers into which the tubes of the outer banks are expanded, outer steam and water drums, steam and water circulators connecting the intermediate drum with the outer drums, connections between said upper headers and the outer steam and water drums, connections between the lower headers and the mud drums, rows of tubes connecting the intermediate steam and water drum with said headers, baffles supported on said tubes, and baffles to direct the gases to the upper part of the inner banks of tubes.
7. In a water tube boiler, two inner banks of generating tubes inclined toward each other so as to form two sides of an A-shaped combustion chamber, a steam and water drum and two mud drums into which the tubes of said banks are expanded, two outer banks of tubes one on each side of the inner banks, upper and lower headers into which the tubes of the outer banks are expanded, outer steam and water drums, steam and water circulators connecting the intermediate drum with the outer drums, connections between said upper headers and the outer steam and water drums, connections between the lower headers and the mud drums, superheaters in the spaces between the inner and outer banks of tubes, and connections between the outer steam and water drums and said superheaters.
- In testimony whereof I have hereunto signed my name in the presence of two subscribing witnesses.
